US0D1109039S

(12) **United States Design Patent** (10) **Patent No.:** **US D1,109,039 S**
(45) **Date of Patent:** **** Jan. 13, 2026**

(54) **HINGE COMPONENT OF A VEHICLE DOOR**

(71) Applicant: **Zoox, Inc.**, Foster City, CA (US)

(72) Inventors: **Timothy David Kentley-Klay**,
Stanford, CA (US); **Nahuel Elias Battaglia**, Stanford, CA (US); **Herman Francisco Delos Santos**, Redwood City, CA (US); **Richard Luke Osellame**, Redwood City, CA (US); **Christopher John Stoffel**, San Carlos, CA (US)

(73) Assignee: **Zoox, Inc.**, Foster City, CA (US)

(**) Term: **15 Years**

(21) Appl. No.: **29/874,360**

(22) Filed: **Apr. 18, 2023**

(57) **CLAIM**

The ornamental design for a hinge component of a vehicle door, as shown and described.

DESCRIPTION

FIG. 1 is a perspective view of a hinge component of a vehicle door shown with disclaimed environment. The design includes a mirror image of the embodiment depicted;

FIG. 2 is an expanded perspective view thereof;

FIG. 3 is an expanded front view thereof;

FIG. 4 is an expanded back view thereof;

FIG. 5 is an expanded left-side view thereof;

FIG. 6 is an expanded right-side view thereof;

FIG. 7 is an expanded top view thereof; and,

FIG. 8 is an expanded bottom view thereof.

The broken lines depict portions of the hinge component of a vehicle door or environment of the hinge component of a vehicle door that form no part of the claimed design.

1 Claim, 8 Drawing Sheets
